WITNESS:

Rene Bruine

INVENTOR

Eugene V. Myers,

By Attorneys,

Haser, Turk & Myers

UNITED STATES PATENT OFFICE.

EUGENE V. MYERS, OF EAST ORANGE, NEW JERSEY, ASSIGNOR TO A. SCHRADER'S SON, INCORPORATED, OF BROOKLYN, NEW YORK, A CORPORATION OF NEW YORK.

DUST CAP OR THE LIKE.

Application filed July 25, 1919, Serial No. 313,146. Renewed September 21, 1922. Serial No. 589,688.

To all whom it may concern:

Be it known that I, EUGENE V. MYERS, a citizen of the United States of America, residing in East Orange, in the county of Essex and State of New Jersey, have invented certain new and useful Improvements in Dust Caps or the like, of which the following is a specification.

This invention relates to dust caps or the like, and aims to provide certain improvements therein.

The invention is particularly directed to dust caps for tire valves of the quick detachable type. In the preferred form, the invention comprises a dust cap having means for frictionally engaging the valve stem or the threads thereof, so that it is capable of being applied by sliding it down over the stem and of being removed by a sliding movement in the contrary direction.

In an application filed by me on even date herewith Serial No. 313,145 I have described a construction in which the cap is provided with a series of spring arms, means being provided for limiting the outward action thereof in order to prevent overstraining of the arms by inadvertent tilting movement of the cap during the act of applying or removing the same.

According to the present invention I provide a construction in which there are a series of spring arms, but instead of such arms being continued to the bottom of the cap, I form the arms above the bottom so that the lower edge of the cap comprises an integral portion circularly intact, whereby strains occasioned by tilting of the cap are taken up by the foot thereof, and the spring arms are thereby prevented from overstraining or undue bending. Preferably also, the arms are enclosed by a sleeve which acts to prevent ingress of dirt or dust through the slots made by the formation of the arms, and also tends to reinforce the ring at the bottom, and also assists in preventing the overstraining of the arms, particularly in certain positions of the cap. The invention includes other features of improvement which will be hereinafter referred to.

Referring to the drawings which illustrate one form of the invention,—

Figure 1 is an elevation of the complete cap;

Fig. 2 is a longitudinal section thereof showing the same as applied to a tire valve;

Fig. 3 is an elevation showing the sleeve in section;

Fig. 4 is a cross-section taken on the line 4—4 in Fig. 2.

Referring to the drawings, let A indicate the cap as a whole, which is shown as formed of longitudinal sections B and C united at D by overlapping flanges. This construction of cap per se forms no part of the present invention, it being the invention of another.

According to the present invention I provide at the foot of the cap a series of spring arms E which are preferably formed by cutting out tongues from the metal forming the cap body and bending them inwardly to a sufficient extent to engage the tire valve stem or casing. The inner face of the tongues may be smooth or roughened, or of other shape such as will permit them to engage the threads of the valve so as to slide thereon. Preferably the ends of the tongues are bent outwardly as shown at F, to facilitate the engagement of the cap as it is moved past the top G of the tire valve casing.

According to the present invention there is left at the bottom of the cap an annular section or ring H which is integrally connected with the body of the cap by strips I. The ring H is, in the case of a drawn cap, circularly intact, and in the case of the two-part cap shown, is cut only in two places, the semi-circular sections thus left retaining a very considerable amount of rigidity. When the cap is applied at the top of the valve casing particularly, there is a danger that in the hands of inexperienced users it may be tilted forcibly to one side. When this is done, before the spring arms have been bent past their elastic limit, the ring H contacts with the valve stem and prevents further movement such as would tend to permanently distort the spring arms.

According to the present invention I provide a cover for the foot portion of the cap, which has the effect of preventing ingress of dust and moisture through the slots made in the formation of the tongue. Such cover is indicated at J, and may be connected with the cap portion in any suitable manner, as by forming a groove K in the cap structure and turning the upper edge L into such groove.

The sleeve J also has the function of forming a reinforcing part for the ring H.

so as to assist in bearing the strains, and further, constitutes a stop for the spring arms, thereby assisting in preventing over-straining of the latter.

5. While I have shown and described one form of the invention, it will be understood that I do not wish to be limited thereto, since various changes may be made therein without departing from the spirit of the 10 invention.

What I claim is:—

1. A dust cap for tire valves or the like comprising a cap portion having a series of 15 spring arms, an integral lower ring portion, and a cover surrounding said spring arms.

2. A dust cap for tire valves or the like having a series of spring arms formed integrally of the metal of the cap, and an integral ring portion beneath said spring arms. 20

3. A dust cap for tire valves or the like comprising a cap portion having a series of integral spring arms, a ring portion beneath said spring arms, and a longitudinally fixed 25 sleeve surrounding said spring arms.

4. A dust cap for tire valves or the like comprising a cap portion having a series of

spring arms, an integral ring beneath said spring arms, and means for limiting the outward movement of said spring arms. 30

5. A dust cap for tire valves or the like comprising a cap portion having a series of 35 spring arms, an integral ring beneath said spring arms, and means for limiting the outward movement of said spring arms, said means comprising a sleeve connected to the cap above said arms.

6. In a dust cap for tire valves or the like comprising a cap portion having a series 40 of spring arms normally extending in a radial direction sufficiently to make a frictional contact with a tire valve casing, a lower ring portion, and a cover surrounding said spring arms.

7. A dust cap for tire valves, or the like, 45 having a series of normally contracted integral spring arms extending downwardly therefrom and adapted to frictionally engage the threads of a valve stem upon being applied thereover, and means for limiting 50 the outward bending of said arms.

In witness whereof, I have hereunto signed my name.

EUGENE V. MYERS.
